PLASTIC HINGE FOR COSMETIC CONTAINERS OR THE LIKE

Roy S. Swenson, Danbury, and Thomas F. Holloway,
Beacon Falls, Conn., assignors to The Rison Manufacturing Company, Naugatuck, Conn.

Filed Apr. 16, 1973, Ser. No. 351,367

Term of patent 14 years

Int. Cl. D8—09
U.S. Cl. D8—189

FIG. 1

FIG. 2

FIG. 3

FIG. 4

FIG. 5

FIG. 1 is an enlarged, broken perspective view of a plastic hinge for cosmetic containers or the like shown broken away for convenience of illustration;

FIG. 2 is a top plan view of the hinge shown in FIG. 1;

FIG. 3 is a side elevational view;

FIG. 4 is a plan view looking at the bottom of the hinge seen in FIG. 1; and

FIG. 5 is an end elevational view.

We claim:

The ornamental design for a plastic hinge for cosmetic containers or the like, substantially as shown and described.
